UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,883, dated November 15, 1887.

Application filed October 15, 1887. Serial No. 252,400. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification, convey to any one accustomed to using paper patterns a clear understanding of how a garment made up by the pattern will appear.

The design shows a basque and a round walking-skirt. The skirt displays a right-side drapery that falls to the edge at its front edge, is lifted in a curve at its back edge, and exhibits draping plaits flaring from the belt in four folds near the front edge and in irregular folds near the back edge; a left-side drapery that falls nearly to the edge of the skirt at its front edge and exhibits draping plaits in its upper and back edges, the side draperies exposing the left side of the front between them to the top; a full back drapery that falls even with the edge all across and exhibits a falling loop in each side edge and loopings to the skirt. The basque exhibits close-fitting fronts that display a closing down the center, a close-fitting back that exhibits its center seam terminating at the waist-line, under-folded plaits at the side edges of the back skirt, and an overlap below each side back seam, coat-sleeves, and a standing collar. The outline of the basque describes a point at the center of the front, a high arch at the sides, and a square position at the back.

What I claim as my invention, and desire to secure by Letters Patent, is—

The design for a lady's costume, as shown in the engraved prints accompanying this specification.
